FABRIC CONSTRUCTION

Gordon W. Rosenberg, Elkins Park, Pa.

Application February 25, 1942, Serial No. 432,338

2 Claims. (Cl. 2—70)

This invention relates to a novel multi-part fabric construction by means of which two fabric parts or members may be secured together without the aid of auxiliary securing devices. The invention, while not limited to any specific use, is especially applicable to garment constructions and when so employed is adapted for a wide variety of uses, both military and civilian, as set forth hereinafter.

The principal object of the invention, therefore, is to provide a novel fabric construction of the above-mentioned character.

Another object of the invention is to provide a novel joint structure in a multi-part fabric construction.

A further object of the invention is to provide a garment construction comprising at least two separable sections and embodying novel means for detachably securing said sections together.

Still another object of the invention is to provide a garment construction of this character which is extremely simple in design and may be constructed very economically, and which is also extremely simple from the standpoint of use or convenience and is adjustable as to height of the wearer.

A still further object of the invention is to provide a garment construction of this character, which, by virtue of its simplicity and other structural features, is well adapted for specialized military uses, such as gas protection.

Other objects and features of the invention will be apparent hereinafter.

In the accompanying drawings:

Fig. 1 illustrates a garment constructed according to the invention, as applied to the body of a user;

Fig. 2 shows the various separable sections of the garment in the specific form illustrated;

Fig. 3 is a fragmentary view of the main sections just prior to their being secured together by the novel means provided by the invention;

Fig. 4 is a similar view showing the sections in associated relation;

Fig. 5 is a sectional view taken along line 5—5 of Fig. 3;

Fig. 6 is a sectional view taken along line 6—6 of Fig. 4;

Figs. 7 and 8 are similar views showing different stages of attachment of the two sections;

Fig. 9 shows a modified form of the invention as applied to sleeve and glove sections of a garment;

Fig. 10 shows the same sections after they have been secured together;

Fig. 11 is a sectional view taken along line 11—11 of Fig. 10;

Fig. 12 is a fragmentary perspective view of a further form of the invention;

Fig. 13 is a fragmentary sectional view of two garment sections constructed according to a still further form of the invention; and

Fig. 14 is a similar view showing the sections secured together.

10 Since the invention is especially applicable to garment constructions, and since one object of the invention is to provide a garment construction embodying the principles of the invention, I have chosen to illustrate and describe the same 15 with specific reference to such adaptation. However, as indicated above, the invention is not limited to such usage.

The invention is based on a simple principle, an explanation of which will enable a clearer 20 understanding of the invention. Let us imagine a body of substantially fixed size, such as a rigid cylinder. Now if a semi-rigid band is placed around such body, and if the circumferential dimension of the band is not greater than the circumferential dimension of the body by more 25 than twice the width of the band, then the band cannot be inverted while on the body except by stretching it (if elastic) or by rolling it over itself. This can readily be understood by imagining a circular band of the above-mentioned character placed about a rigid cylinder. Thus the band, by virtue of its semi-rigid nature, will tend 30 to maintain its original position and will resist turning.

35 According to the present invention, this principle is utilized to secure two fabric members together. A semi-rigid band of predetermined circumferential dimension is provided at the edge of each member, and the two bands placed 40 in juxtaposed relation about a body and are rolled or turned simultaneously. If the dimension of each band is related to the circumference of the body as above-mentioned, the bands become interlocked in a self-sustaining joint which 45 maintains the fabric members together until they are forceably separated. With the foregoing explanation in view, reference may now be had to the accompanying drawings.

Referring first to Figs. 1 and 2, there is illustrated a multi-part garment constructed according to the invention and comprising at least a blouse section 1 and a trouser section 2 which are adapted to be secured together in the manner above-mentioned. As illustrated in Figs. 1 and 2 these two sections have detachable gloves

3 and boots 4 which are attachable respectively to the blouse and trouser sections in the same manner. However, the glove and boot sections may be permanently secured to the main sections, the purpose of the illustration merely being to indicate that the novel joint structure may be employed in conjunction with auxiliary parts of the garment.

Referring to the blouse section 1, there may be provided a helmet 5 which may be permanently or removably attached to the blouse section in any suitable manner. The helmet is provided with a transparent portion 6 to accommodate the eyes of the wearer. For ordinary usage the portion 6 may be an opening through which the wearer may see and breathe. However, for special purposes such as gas protection, the helmet may be suitably equipped, for example it may comprise a gas mask.

The blouse section is adapted to be slipped over the head and shoulders of the wearer, and it is of sufficiently large circumferential dimension to permit this. For the same reason the blouse section is substantially uniform in circumferential dimension from the shoulder to the waist.

The trouser section 2 is adapted to be slipped onto the lower part of the user's body with a maximum of ease and, therefore, this section is also sufficiently large in circumferential dimension for this purpose.

Both sections of the garment may be formed of any suitable material and they are of very plain construction with a minimum of seams and are entirely free of pleats, flaps, buttons, etc.

In accordance with the present invention, both of the sections 1 and 2 are extended at the waist portion, and preferably each section is extended at least 6 inches beyond the normal waist line. Each section is provided at the edge of the waist portion with a semi-rigid band 7 and 8, and the relative circumferential dimensions of the two sections are such that the edge portion of one may be inserted in the edge portion of the other. Preferably the waist portion of the blouse section is slightly larger in circumferential dimension than the waist portion of the trouser section, as illustrated in Fig. 2.

The band of each section may comprise a separate piece attached to the garment section but it is preferably formed by folding the edge portion of the garment section, as shown in Fig. 5, and by providing rows of heavy stitching 9 to impart the desired degree of stiffness to the band. Any other means of imparting a semi-rigid stiffness to the band may be used, such as the use of an insert of stiff fabric, hair cloth, whale bone or even wire inserts. Although each band may be continuous, it is preferred to interrupt the band at one or more places as shown at 10, 11 and 12 of Fig. 2 in order that the band may be adjusted in relation to the size of the wearer's waist. In the illustration of Fig. 2, the portions 10, 11 and 12 are parts of the garment proper and the band sections 7 and 8 are provided with hook and eye fasteners indicated generally at 13, in order that the band sections may be brought together, as shown in Fig. 3. However, any suitable means for adjusting the size of each band may be employed. For example, portions 10, 11 and 12 may comprise elastic sections adapted to adjust each band automatically to the waist of the wearer. As shown in Fig. 5, the band 7 is preferably formed by folding the material inward, while the band 8 is formed by folding the material outward. The reason for this will appear shortly.

Assuming that the two garment sections 1 and 2 have been placed on the wearer's body, the wearer proceeds as follows to adjust and secure the sections together. The band 8 is first reduced in size, assuming that the particular adjusting means employed requires manual manipulation, so that the band is related to the circumferential dimension of the wearer's waist as described above. The band 7 is then placed over band 8 as shown in Figs. 4 and 6, and band 7 is likewise adjusted. With one band inserted within the other and with the two in juxtaposed relation as in Figs. 4 and 6, the two bands are simultaneously turned or inverted as shown in Figs. 7 and 8. Fig. 7 shows the bands and adjacent portions of the garment sections after one inversion has been made, while Fig. 8 shows the parts after two inversions have been made. By reason of the semi-rigid nature of the two bands, this folding process may be easily performed. By providing two or more folds, the garment sections may be securely interlocked and they will remain secured together by virtue of the resistance of the bands to turning as previously described. As shown in Figs. 6 to 8, the edge portions of the garments containing the bands are preferably rotated or folded in such direction that the fold on the outside of the garment is downward. This enables water to run down the outside of the garment without lodging in the folded joint.

It is important to note that the folded joint provided by this construction, as shown in Fig. 8, provides a tight seal and also provides small spaces 14 within which air is trapped, thus, providing a sort of air seal entirely around the waist of the wearer. The joint may comprise as many folds as are necessary to adapt the garment to the height of the particular wearer and, of course, the greater the number of folds, the greater will be the sealing effect. This feature is important in certain usages of the garment.

Where the garment has detachable glove and boot sections, as shown in Fig. 2, these sections may be joined to the main sections in the same manner as described above.

The joint structure is capable of various modifications. For example, only one of the bands need be semi-rigid, although it is preferred to have them both of this character as it gives a better joint. Either or both of the bands may be circumferentially elastic, in whole as well as in part, and in such case the tension or stretch of the band on the outer side, against the inner band, will tend to keep them interlocked.

Where no elastic means of circumferential adjustment is provided, the portions 10, 11 and 12 are purposely made flexible so that when the juxtaposed bands are folded over, the one on the inner side can adjust automatically to a slightly shorter length than the outer one, and thus avoid binding, each band in turn adjusting itself as they are folded over.

Portions 10, 11 and 12 could be omitted entirely, leaving spaces instead, in one or both of the bands. One or both of the bands would then be fragmentary but none-the-less usable according to the invention.

From the foregoing description, it may be seen that the garment construction provided by the invention is capable of a wide variety of uses, but it is particularly adapted for military uses. From the standpoint of civilian use, the novel securing means may be employed in any instance where it is desired to secure two sections of a garment together. However, the garment con-

struction as a whole is particularly adapted for weather-resistant uses. For example such a garment is admirably suited for use as a skiing garment.

In respect to military use, the garment construction is particularly adapted for use by aviators, ski troops, etc., and it is especially well suited for gas decontamination workers. In the latter case the garment may be constructed of gas-proof material of any known type. Because of its simplicity of construction, the garment lends itself very well to this usage. Moreover, the novel means for securing the garment sections together provides a sealed joint, as pointed out above, which is an important feature from a standpoint of gas protection, and at the same time may be readily removed.

Although the invention is particularly adapted for use in a garment, it is applicable to other uses wherein tubular fabric parts are used. For example, it could be applied to tarpaulin covers for cylindrical objects such as plane motors, duffle bag covers, canvas air duct hose, etc.

In Figs. 9 to 11, there is illustrated a further embodiment of the invention, and although it is illustrated as applied to sleeve and glove sections 15 and 16 of a garment, it is equally well adapted for securing together any such fabric sections. In this instance the garment sections are formed substantially as above and are provided with bands 17 and 18, one adapted to fit within the other. However, there is further provided a flap 19, which is preferably semi-rigid, on the sleeve section 15 in predetermined spaced relation to the band 17. When the edge portions are interfitted and folded as shown in Figs. 10 and 11, the flap 19 is adapted to retain the folded portions, thus further assuring that the interlocking relation will be retained as long as desired. As may be seen from Fig. 11, it is only necessary to insert the upper part of the fold under the flap 19.

Preferably the band 17 is provided on a separate piece 20, and the flap 19 is formed by folding a portion of section 15, as shown in Fig. 11. It is then possible to use an inserted strip 21 within flap 19 to stiffen the same. If desired a similar flap could be used in conjunction with piece 22, and the two flaps would then hold both of the interfolded bands in place. By forming at least a portion of sections 20 and 22 of material which is elastic in width, and if desired in circumference also, the folded joint may be caused to fit even more snugly under flap 19. It is also possible to employ fastening means to secure the edge of the flap to the folded joint after the parts have been fully assembled.

In Fig. 12, there is shown a further embodiment of the edge portions of two fabric sections 23 and 24, having bands 25 and 26 respectively. In this instance a piece of felt 27 or the like is stitched to band 25 and lies along the one side of section 23. When the edge portions are

folded as above described to interlock the sections together, the soft material 27 fills the spaces or interstices within the joint, making the joint even more secure and providing a tighter seal. This feature is particularly desirable where the joined sections are constructed of fairly stiff material, and the joint would not normally be as tight as is desired.

In Figs. 13 and 14, there is shown a further form of the joint structure in which fabric sections 28 and 29 are provided with complementary bands 30 and 31 of equal circumferential length. In this instance, the bands are disposed in edge-to-edge relation, as shown in Fig. 13, and they are then folded to obtain the joint of Fig. 14. If desired, a flap 32 may be provided on one section for the purpose previously described.

Thus, it will be seen that the invention provides a construction which is capable of various modifications and is adapted for a wide variety of uses. It will be understood, therefore, that the invention is not limited to the specific forms illustrated nor to any particular use.

I claim:

1. A garment construction comprising at least two separable sections adapted to envelope adjacent parts of a wearer's body, said sections having complementary edge portions adapted for disposition one within the other, a semi-rigid band on each of said edge portions for detachably securing said sections together by foldably interlocking said portions, and a flap on at least one of said sections in predetermined spaced relation to the band thereon and adapted to retain the folded portions in place, at least a portion of the interlocking edge portions being formed of material which is elastic transversely of the circumferential joint, whereby a tighter seal is imparted to the joint.

2. A fabric construction adapted to enclose a body and comprising tubular, flexible, fabric members having their end portions telescopically interfitted, at least one of said members having a part of its end portion relatively stiffer than the flexible fabric of said members and being of such resiliency as to be capable of folding simultaneously with and within the fabric of said members, said interfitted end portions being jointly folded with and within the fabric of said members whereby to form a separable joint between said members, said relatively stiffer end portion defining a flat core member which facilitates folding, and said core member having a circumferential dimension greater than that of the body enclosed within said members by less than twice the width of the core member, whereby the joint is substantially incapable of unfolding and said core inhibits unfolding of the joint under longitudinal stress and independently of the body enclosed within said members.

GORDON W. ROSENBERG.
